UNITED STATES PATENT OFFICE

CARMI J. STEELE, OF LOS ANGELES, CALIFORNIA, ASSIGNOR OF ONE-THIRD TO WALTER R. COATES AND ONE-THIRD TO ROY C. TROEGER, BOTH OF LOS ANGELES, CALIFORNIA

DESIGN FOR A PEDESTAL LAVATORY

Application filed May 28, 1930. Serial No. 35,813. Term of patent 14 years.

To all whom it may concern:

Be it known that I, CARMI J. STEELE, a citizen of the United States, residing at Los Angeles, in the county of Los Angeles and State of California, have invented a new, original and ornamental Design for Pedestal Lavatory, of which the following is a specification, reference being had to the accompanying drawing, forming part thereof.

The figure is a perspective view of the article showing my new design.

I claim:

The ornamental design for a pedestal lavatory, as shown.

CARMI J. STEELE.
